UNITED STATES PATENT OFFICE.

SALIM N. MALLOUK, OF BROOKLYN, NEW YORK.

DESIGN FOR A LACE SCARF OR THE LIKE.

Application filed December 18, 1926. Serial No. 20,073. Term of patent 7 years.

To all whom it may concern:

Be it known that I, SALIM N. MALLOUK, a citizen of the United States of America, and a resident of the borough of Brooklyn, Kings County, city and State of New York, have invented a new, original, and ornamental Design for a Lace Scarf or the like, of which the following description, in connection with the accompanying drawing, is a specification.

The single figure of the drawing is a plan view of approximately one-half ($\frac{1}{2}$) of a lace scarf or the like showing my new design. The opposite end of the scarf is substantially a repetition of the design shown in the end of the scarf illustrated in the single figure of the drawing.

I claim as my invention:

The ornamental design for a lace scarf or the like, substantially as shown and described.

SALIM N. MALLOUK.
